(57) **CLAIM**

An ornamental design for a learner permit driver identifier decal or magnet, as shown and described.

DESCRIPTION

FIG. 1 is a front view of a learner permit driver identifier decal or magnet, in accordance with aspects of the present invention;

FIG. 2 is a side view of a learner permit driver identifier decal or magnet, in accordance with aspects of the present invention;

FIG. 3 is a top view of a learner permit driver identifier decal or magnet, in accordance with aspects of the present invention. The bottom view is identical thereto;

FIG. 4 is a back view of a learner permit driver identifier decal or magnet, in accordance with aspects of the present invention;

FIG. 5 is an elevation of a learner permit driver identifier decal or magnet of FIG. 1 attached to a rear window of an automobile;

FIG. 6 is an elevation view of a learner permit driver identifier decal or magnet of FIG. 1 attached to a rear bumper of an automobile;

FIG. 7 is an elevation view of a learner permit driver identifier decal or magnet of FIG. 1 attached to a rear body portion of an automobile; and,

FIG. 8 is an elevation view of a learner permit driver identifier decal or magnet of FIG. 1 attached to a license plate of an automobile.

In the drawings, the broken lines illustrate environment and form no part of the claimed design.
